PASTER UNIT

Sigurd Clausen, Brooklyn, N.Y., assignor to International Cigar Machinery Company, a corporation of New Jersey

Application November 22, 1957, Serial No. 698,242

11 Claims. (Cl. 131—82)

This invention relates to cigar manufacture and more particularly to applying paste to a portion of a cigar bunch.

One type of cigar on the market has a mouthpiece tip usually formed from wood or plastic. This type has a "flat" mouthpiece portion and a cylindrical portion which receives the tip of the bunch and is enfolded within the wrapper leaf. The tip is thus retained by the contained bunch tip and the overlying wrapper leaf. However, in the case of mouthpiece tips made of plastic the surface of the plastic is frequently so smooth and slippery that additional holding means are required.

It is therefore an object of this invention to apply additional holding means such as paste or glue to the top of a cigar bunch prior to the application of the mouthpiece tip and wrapper.

It is a further object of the invention to provide a simple and inexpensive structure that may be placed on a conventional cigar machine which will receive its motion and timing from the cigar machine and apply a small amount of paste or glue to a bunch tip at a suitable time.

More particularly, it is an object of my invention to devise a mechanism having a source of paste or glue, and a paste applier with operating means readily connectable to a single moving part of the cigar machine and operated therefrom.

It is an object of the invention to have the device operate from a unitary motion on a cigar machine.

It is an object of the invention to have the device operate from a unitary oscillating or crank motion which may exist on a cigar machine and be related to the timed cycle of the cigar machine.

It is more specifically an object of the invention to devise a unit that may be mounted adjacent the mold turret of a cigar machine to apply paste to a cigar bunch in the mold turret just prior to its ejection therefrom.

It is an object of the invention that said device be operated from the transfer mechanism to the mold turret.

The novel features which I believe to be characteristic of my invention are set forth with particularity in the appended claims. My invention itself, however, both as to its organization and method of operation may be understood by reference to the following description taken in connection with the appended drawings, in which:

Fig. 1 is a side elevation partly in section of the paster unit shown in conjunction with rotating cigar mold turret and bunch inserting and ejecting mechanism;

Fig. 2 is a sectional side elevation of the paster unit;

Fig. 3 is a plan view of the paster unit and its actuating mechanism shown in conjunction with a cigar mold turret;

Fig. 4 is a sectional end elevation through a single bunch mold of the turret illustrating the paste applying device; and

Fig. 5 is a sectional plan view showing the spring-loaded paste transfer dipper mechanism in detail.

Referring now to Fig. 1, mold turret 10 carries about

2

its periphery a plurality of molds 12 in which cigar bunches 14 are inserted by the transfer mechanism generally designated by 16. The mold turret is intermittently rotated in a counterclockwise direction as indicated by the arrow in Fig. 1 to cause alternate periods of movement and rest. As the mold turret is indexed each individual bunch 14 eventually arrives at the position indicated by the mold 12b. In this position it is ejected as by the conventional ejector mechanism generally indicated at 18 into the transfer jaws 20 of the transfer mechanism generally indicated at 22. The mouthpiece may be applied to the bunch while the same is held in the transfer 22. Since the operation of the ejector 18 or the transfer 22 does not form a part of this invention further discussion of these parts is felt unnecessary. However, the operation of these devices may be understood by reference to Patent No. 2,633,134, issued to J. F. Halstead, dated March 31, 1953, and Patent No. 2,443,453, issued to J. F. Halstead, dated June 15, 1948.

As shown in Fig. 1, the paster unit generally designated as 24 operates on the bunch 14 in the mold indicated by the position 12a. The paster unit 24 is mounted on a supporting bracket 28 secured to a flange of the turret housing 26 of the cigar machine. A bearing block 30 is secured to the bracket 28 by the screws 32. The paste reservoir 34 is supported on the bearing block 30 by the bracket 36.

Secured in a boss 38 of bearing block 30 is a stud shaft 40 on which is pivotally mounted an arm 42. To arm 42 is pivotally connected one end of a link 44 while the other end carries a stud shaft 46 fixed thereon. Secured to stud shaft 46 is also a paster finger 48, while pivotally connected to the same shaft is the free end of a suitably shaped arm 50 of a double lever 52 mounted on a stud shaft 53 rotatably supported in bearing block 30. The free end of the other arm 54 of the double lever 52 is pivotally connected to one end of an operating link 56 while the other end of the same is pivotally connected to the free end of an actuating arm 59 mounted on an oscillating shaft 158.

Mounted in bearing block 30 and projecting therefrom is a stud shaft 58 which loosely supports a suitably shaped paste supply lever 60 the free end of which is provided with a dip lug 62. The paste supply lever 60 is also provided with a torsion spring 64 which surrounds the head end portion of the stud shaft 58 and which is confined in a suitable bore in the hub of lever 60 (Fig. 5). One end of this torsion spring 64 is anchored to the head end of the stationary stud shaft 58 while the other end 50 engages with a suitable hole in the hub of lever 60 thus urging the latter in a clockwise direction with its dip lug 62 close to the bottom of the paste reservoir 34 as illustrated in Fig. 1 of the drawings. The paste supply lever 60 is arrested at this position by means of a pin 66 projecting from the hub of lever 60 and engaging a stop pin 68 mounted in bearing block 30 and extending into the path of the pin 66. To stud shaft 53 is also secured a paste control lug 70 which is so arranged that its free end extends in line beneath the pin 66 projecting from the paste supply lever 60. Upon clockwise rotation, transmitted by stud shaft 53, control lug 70 will contact and raise the pin 66 thereby lifting the dip lug 62 of the paste supply lever 60 from the paste reservoir 34 as illustrated in Fig. 2.

It is self-evident that the entire paster unit with the connections and linkages described above is actuated in a proper timed relation by the oscillating actuating arm 59 on shaft 158 (Figs. 1 and 3). The oscillating actuating arm 59 moves in timed relation to the intermittent indexing of the mold turret. While a more complete understanding of the operation of the transfer device may be obtained by reference to the Patent to Halstead 2,443,453, dated June 15, 1948, the following explanation is

thought sufficient to provide an understanding of its co-operative action in the present invention. The reference numerals used herein on the transfer device are the same as those of the aforesaid Halstead patent for simplicity in comparing the two.

Transfer mechanism 15 is operated by means of a cam actuated gear segment 102 and a cam actuated arm 170. Gear segment 102 is employed to oscillate the gear 100 mounted on the shaft 82 to which the transfer mechanism is secured. Figure 1 illustrates the insertion of a cigar bunch 14 into a mold at position 12c of the mold carrying turret 10. The inserting plunger shank 148 is actuated by means of an arm 156 mounted on the oscillating shaft 158 which is actuated through an arm 166 and a link 168 by the cam actuated arm 170. The latter as well as the cam actuated gear segment 102, of course, are properly timed with the intermittently rotating mold turret 10 to permit the plunger 146 of shank 148 to enter the mold at 12c to deposit a cigar bunch 14. The oscillating motion of shaft 158 during the bunch inserting operation transmits its oscillating motion to the arm 59 which in turn through link 56 will effect the operation of the paste applying finger 48 as well as of the paste supply lever 60.

Operation

Referring to the position shown in Fig. 2 the link 56 is at the end of its movement to the left and the double lever 52 has been rotated clockwise to the limit of its rotation in that direction. The cam lug 70 by contacting the pin 66 has raised the paste supply lever 60 to its uppermost position to permit a contact of the tip of paste applying finger 48 with the dip lug 62 to effect a transfer of a small amount of paste to said paste applying finger 48.

During each dwell of the intermittently rotating turret the oscillating shaft 158 is caused to rotate in a counter-clockwise direction to effect the insertion of a bunch 14 in the mold 12c (Fig. 1). This movement transmitted by the arm 59 moves the link 56 toward the right from the position shown in Fig. 2. In turn, this causes the double lever 52 to rotate counter-clockwise about its pivot point thereby causing the paste applying finger 48 to swing with its free end into the mold to apply paste to the head end of the bunch as shown in Fig. 1. Simultaneously cam lug 70 lowers the pin 66 down upon stop pin 68 permitting torsion spring 64 to urge dipper lug 62 into the paste pot 34. Before the mold turret 10 resumes its intermittent motion shaft 158 is turned in a clockwise direction to effect a raising of ejecting plunger 148 from said mold. This movement is transmitted to link 56 to return the paste applying finger 48 and paste supply lever 60 to their original positions shown in Fig. 2, thereby completing the cycle of the paster unit in timed relationship to the movement of the mold turret.

I claim:

1. In combination, a cigar machine having a mold turret and a reciprocating plunger operatively movable to insert cigar bunches in said turret, a paster device comprising a reservoir, a dipper and a paster finger, said dipper being movable into and out of said reservoir, said paster finger being swingable from a position contacting a bunch in said mold turret to a position contacting said dipper, means to operate said finger and said dipper in timed relation, and a single connecting member connecting said reciprocating plunger to said operating means.

2. In a cigar machine having a mold turret which is rotated intermittently to cause alternate periods of movement and rest and a device associated with said turret and operative during the periods of rest to move to perform an operation thereon, a paster unit comprising a paste reservoir, a member movable into and out of said reservoir, a paster finger movable to transfer paste from said member from a position outside of said reservoir to an article in said mold turret,

unitary means to move said member and said paster finger in timed relation to each other, said means being operably connectable to said device to move said member and said finger, said finger moving to an article in said mold turret during the periods of rest of said turret.

3. The combination in a cigar machine of an intermittently moving mold turret having molds thereon for shaping a cigar bunch, said mold turret being indexed through successive work operation stations, a first station having a reciprocating transfer device to place cigar bunches in said mold turret, a last station for the ejection of cigar bunches rotatably positioned in advance of said first station, a paster unit positioned just prior to said last station and having paster applying means to apply paste to a portion of a cigar bunch in said mold turret, said paster applying means being operatively connected to said reciprocating transfer to be actuated therefrom and in timed relation thereto and to said mold turret.

4. A device substantially as set forth in claim 3, further characterized in that said paster unit comprises a paste reservoir, a member movably mounted to move into and out of said reservoir, a paste applying finger, an operative parallel linkage, said paste applying finger being connected to said parallel linkage so that moving of said parallel linkage will move said paste applier finger from a point crossing the arc of movement of said member to a cigar bunch supported in said mold turret, means on said parallel linkage to move said member operatively into and out of said reservoir, said means in said parallel linkage being constructed and arranged to bring the operative tips on said dipper finger and said paster finger into contact outside of said reservoir on one movement of said parallel linkage and to move said dipper finger into said reservoir and said paste applying finger to a cigar bunch in said mold turret during the opposite movement of said parallel linkages, and at least one link to operatively connect said parallel linkages to said reciprocating transfer whereby said paster device may operate in timed relation to the intermittent movement of said mold turret.

5. An accessory device securable to a cigar machine comprising a unitary bracket supporting a paste reservoir, a dipper finger pivoted on said bracket to swing its free end into and out of said paste reservoir, a member pivoted on said bracket having means thereon to contact said dipper finger to move it into and out of said reservoir, said lever supporting the paster finger and having a free end, said fingers in said lever being so constructed and arranged that movement of said lever in one direction raises said dipper finger and swings said paster finger so that its free end contacts a portion of said dipper finger raised from said reservoir and movement in the other direction returns said dipper finger to said reservoir and moves the free end to a paster applying position, and means to connect said lever to a crank motion.

6. A device substantially as set forth in claim 5 further characterized by resilient means yieldably urging said dipper finger in one direction of movement.

7. The combination with a mold turret having molds thereon for supporting and shaping a cigar bunch, drive means to intermittently drive said turret to cause alternate periods of movement and rest, a source of paste, a paster finger movable from said source into a mold to apply paste to a bunch supported therein, and means operative in timed relation to the drive means of said turret to move said finger whereby said finger will enter a mold during the periods of rest of said turret rotation.

8. In a cigar machine having a mold turret having molds for supporting and shaping cigar bunches, work operation devices associated with said turret, drive means to intermittently drive said turret and to operate said work operation devices during the time between the intermittent drive of said turret, a source of paste, a finger

movably mounted to swing between said source and a mold positioned at a predetermined station during the intermittent rotation of said turret, and means connected to said work operation device to move said finger from said source to said station during the operation of said device whereby the movement of said finger is timed to the intermittent drive of said mold turret.

9. In combination on a cigar machine, an intermittent-
ly driven mold turret having molds thereon for supporting and shaping a cigar bunch, work operating devices positioned about the periphery of said turret at predetermined stations, said devices being timed to operate during the time between the intermittent drive of said turret rotation, a source of paste positioned near said turret, a paste finger movably mounted to move from said source of paste to a predetermined station to enter a mold to apply paste to a cigar bunch therein, and means connected to at least one of said devices to move said finger into said cigar bunch upon operation of said device whereby said finger operates in timed relation to the said time between the intermittent drive of said turret rotation.

10. In a cigar machine, a mold turret having molds thereon for supporting and shaping a cigar bunch, means to intermittently drive said mold turret, work devices operatively mounted about said mold turret to perform work operations on cigar bunches at predetermined stations and during the time between the intermittent drive of the turret, a source of paste mounted near said turret, a member movable into and out of said source of supply, said member having a position in said source of supply to receive paste and a position outside of said source of supply, a finger movable from said member at its posi-
25
30

tion outside of said source of supply to a cigar bunch at a predetermined station during the said time between the intermittent drive of said mold turret, unitary means in which said member and said finger are operable, and drive means connectable to one of said devices to operate said unitary means and to move said finger to a cigar bunch supported in a mold during the said time between the intermittent drive of said mold turret.

11. In a cigar machine having an intermittently rotat-
ing mold turret having molds therein for supporting and shaping cigar bunches, means adjacent said turret and operative to perform a work operation at a predetermined station during the time between the intermittent drive of said turret rotation, a source of paste, a mech-
anism movable to withdraw a small quantity of paste from said source, means movable to contact said mech-
anism to receive a small quantity of paste therefrom and to move with said paste into a mold at a predetermined station during the said time between the intermittent drive of said mold turret to apply paste to a bunch therein, and means to connect said movable means to said work operation device to move said movable means into said mold in timed relation to the said time between the intermittent drive of said turret.
